UNITED STATES PATENT OFFICE.

ELISABETH CHURCHILL WARD, OF EUTAW, ALABAMA.

DESIGN FOR A COTTON-BOLL SOUVENIR.

SPECIFICATION forming part of Design No. 34,559, dated May 28, 1901.

Application filed April 29, 1901. Serial No. 58,097. Term of patent 3½ years.

To all whom it may concern:

Be it known that I, ELISABETH CHURCHILL WARD, a citizen of the United States, residing at Eutaw, in the county of Greene and State of Alabama, have invented and produced a new and original Design for a Cotton-Boll Souvenir, of which the following is a specification.

This invention relates to a new and original design for a souvenir; and the essential feature resides in having a rounded object resembling a head projecting from a soft-appearing support.

In the drawings, Figure 1 is a perspective view of a souvenir embodying the features of the design and looking toward the front thereof. Fig. 2 is a similar view of the same souvenir looking toward the back of the same.

The design is characterized by a soft-appearing or fluffy support 1, having a holding projecting portion 2 extending from the lower portion thereof. From the said support a rounded object 3, resembling a human head, projects and is embellished with a face.

Having thus described the invention, what is claimed as new is—

The design for a souvenir, as herein shown and described.

In testimony that I claim the foregoing as my own I have hereto affixed my signature in the presence of two witnesses.

ELISABETH CHURCHILL WARD.
